CAR TRUCK

Rudolph Leppla, Davenport, Iowa, assignor, by
mesne assignments, to McConway & Torley
Corporation, Pittsburgh, Pa., a corporation of
Pennsylvania

Application April 3, 1941, Serial No. 386,702

5 Claims. (Cl. 105—190)

This invention relates to car trucks of the so-called swing motion type in which the bolster is supported upon springs carried by supporting members pivotally suspended from a transom extending across the space between the truck side frames, and particularly to trucks for freight cars designed to carry heavy loads.

The present invention relates particularly to trucks of the type described in my copending application, Serial No. 382,955, filed March 12, 1941, in which the truck is provided with superposed sets of cushioning springs, one set interposed between the bolster and transom and the other set interposed between the transom and side frame; and in which means is provided for stopping off the springs of one set before the springs of the other set are fully compressed in order to provide a car which is easy riding when lightly loaded, and to provide an effective spring cushion for the car through a wide range of loads.

The present invention has for its principal objects to provide improved mounting for the transom in the side frames of the truck and to provide an improved spring support for the transom.

With the above and other objects in view, the invention may be said to comprise the car trucks as illustrated in the accompanying drawing, hereinafter described and particularly set forth in the appended claims, together with such variations and modifications thereof as will be apparent to one skilled in the art to which the invention pertains. Reference should be had to the accompanying drawing forming a part of this specification, in which:

Figure 1 is a fragmentary side elevation of a truck embodying the invention, portions of the side frame and transom being broken away and shown in vertical section;

Fig. 2 is a fragmentary top plan view showing one end of the transom and the portion of the side frame in which the end of the transom is mounted; and

Fig. 3 is a section taken on the line indicated at 3—3 in Fig. 1.

In view of the fact that the side frames of the truck and the supports for opposite ends of the transom, spring plank and bolster are identical, the accompanying drawing shows the construction at one side of the truck only, it being understood that the construction shown is duplicated at the opposite side of the truck as is the usual practice in car truck constructions.

Referring to the accompanying drawing, the

truck of the present invention has a bolster A upon which the car body is supported, a spring plank B which carries supporting springs upon which the ends of the bolster A rest, a transom C from which the spring plank is pivotally suspended, and side frames D in which the ends of the transom are slidably mounted.

Each side frame D has an upper compression chord 1 and a lower tension chord 2 which connect journal boxes 3 located at opposite ends of the frame. The chords 1 and 2 are connected intermediate their ends by spaced guide columns 4 which provide a central opening in the side frame midway between the ends thereof. The guide columns 4 have widely spaced vertical guide portions 5 adjacent the bottom chord 2 and vertical guide portions 6 at their upper ends which are offset inwardly with respect to the lower guide portions 5, providing a transom receiving space at the top of the opening considerably narrower than the space between the guide portions 5 of the columns. The upper and lower guide portions 5 and 6 of the columns 4 are connected by upwardly converging inclined portions 7. The bottom chord 2 is curved throughout its length so that the portion thereof between the lower end portions 5 of the columns is downwardly arched. The chord 2 has a bottom web 8 and the portion of the chord between the lower ends 5 of the columns 4 is in the form of an upwardly opening channel consisting of the bottom web 8 and upright side flanges 9. The flanges 9 have upwardly extending guide portions 10 adjacent the lower guide portions 5 of the columns and between the projecting portions 10 and throughout the major portion of the width of the opening the flanges 9 have horizontal top edges 11 which provide transom seats.

The transom C has two crossbeams 12 which extend across the space between the side frames D and which are spaced apart to receive the bolster A between them. The bolster A has end portions guided for vertical movement between the crossbeams 12, the crossbeams having vertical inner faces 13 which serve as guides for the bolster. The crossbeams 12 are rigidly connected at their ends by members 14, which are the upper crossbars of rectangular transom guide frames which slidably fit within the side frame openings. Each transom guide frame has vertical side bars 15 and a base member 16 connecting the lower ends of the side bars. The top bar 14, side bars 15 and base member 16 of the transom guide frames provide a substantially rectangular window in the transom end frame

through which access may be had to the bolster supporting springs. The transom with its end frames may be in the form of a one-piece casting.

The crossbeams 12 are provided with shoulders 18 at the ends thereof which overlie the inner sides of the vertical guide portions 6 of the guide columns 4. The side bars 15 of each transom guide frame have lateral projections 19 adjacent their lower ends which provide a widened base portion for the transom guide frame which is guided between the lower vertical portions 5 of the guide columns. The projections 19 are received between the projecting guide flanges 10 of the bottom chord. The transom end frames are also provided with depending flanges 20 on the base portion 16 which overlap the flanges 9 of the bottom chord. The shoulders 18, guide flanges 10 and flanges 20 guide the transom in the side frame and cooperate to hold the transom against angular movements with respect to the side frames.

Within the channel portion of the bottom chord, there is mounted a semi-elliptic leaf spring 21 which has a central band 22 which is seated between lugs 23 on the bottom web 8. The opposite ends of the leaf spring are curved upwardly away from the web 8 and provided with end portions 24 which bear against the bottoms of the projections 19 to yieldably support the transom. The spring 21 is housed within the channel portion of the bottom chord and normally supports the transom with its base portion 16 spaced above the top edges 11 of the bottom chord flanges. However, when a predetermined load is imposed upon the transom, the spring 21 is compressed sufficiently to permit the transom to seat upon the bottom chord.

The spring plank B is suspended from the transom C by means of links 25 which are connected at their upper ends to the crossbeams 12 by pivots 26 and at their lower ends to the spring plank B by pivots 27. Cushioning springs of any suitable type may be interposed between the spring plank B and the bolster A. As herein shown, the spring support for the bolster may be in the form of a nest of compression coil springs 28. The strength and deflection characteristics of the spring 21 are such that when the transom is placed upon the spring the transom will move downwardly until the projections 19 are positioned in the spaces between the guide flanges 10. Sufficient clearance is provided between the projections 19 and the inclined portion 7 of the guide columns to permit the transom to be lifted to a position in which the projections 19 are clear of the flanges 10 to permit easy placement or removal of the side frames.

By providing a spring 21 of the proper deflection characteristics, the seating of the transom on the bottom chord can be made to occur under any desired load, which in any case will occur before the crushing point or safe stress limit of the spring has been reached.

When the load upon the truck is not sufficient to compress the springs 21 into the channels of the bottom chords and seat the transom on the bottom chords, the total deflection of the car body is the sum of the compression of the springs 21 under the given load and the compression of the springs 28 under the same load. The two sets of springs thus provide a car body support which permits the bolster and car body to have a greater range of movement and provide a more yieldable

cushion than would be provided by either set of springs alone.

This increased deflection is very advantageous in that it provides easy riding qualities in a lightly loaded car. For example, if the bolster cushioning springs are designed to provide effective cushioning action with a heavily loaded car, the combined action of the springs 21 and 28 may provide an effective cushion for the car when empty or lightly loaded.

The bolster and transom cushioning springs can be readily removed and replaced with other springs of different capacity. For example, if it is desired to employ a car for carrying loads lighter than those for which the trucks were originally designed, the transom springs, or both the transom and bolster springs may be replaced with springs having the capacity and amplitude of movement suitable for the lighter load.

The transom springs 21 are preferably more yieldable than the bolster springs, but may if desired be of sufficient stiffness to allow for some deflection beyond that resulting from a fully loaded car. Under these conditions the transom cushioning springs do most of the cushioning and the relatively stiffer bolster supporting springs have a snubbing effect when the transom seats on the side frames because of excessive impacts. Also, vibrations are damped by reason of the differences in the periods and amplitude of the vibration of the two sets of cushioning springs.

The side frames are easily removed by simply jacking up the transom to its uppermost position, in which position the projections 19 are clear of the flanges 10 and the flanges 20 are clear of the flanges 9.

To prevent the truck from getting out of square, there must be close cooperation between the side frames and the members which connect them. In a truck of the present invention, the depending flanges 20 together with the projections 19 cooperate with the side frames to prevent angular movement between the transom and the side frames in a horizontal plane. Because of the fact that the projections 19 are widely spaced, considerable clearance can be allowed between these projections and the guide flanges 10 so as to permit free vertical movement of the transom without permitting any substantial horizontal angling.

It is to be understood that variations and modifications of the specific device as herein shown and described for purposes of illustration may be made without departing from the spirit of the invention.

What I claim is:

1. In a car truck, a side frame having a top chord, a bottom chord and spaced guide columns forming a central opening in the frame, the portion of the bottom chord between said columns being in the form of an upwardly opening channel with a web which curves upwardly from the center toward the ends of the chord and upright side flanges which have horizontal top edges throughout the major portion of the space between the columns and which have upwardly projecting guide portions adjacent the columns, a semi-elliptic leaf spring having a central portion seated upon the web of the bottom chord substantially midway between the columns and end portions curved upwardly away from said web and terminating adjacent the columns between the upwardly projecting portions of said flanges, and a transom having an end portion guided for vertical movement in said opening,

the end portion of the transom having portions extending into the spaces between the upwardly projecting portions of said flanges and resting upon said springs and a flat seating portion engageable with the top edges of said flanges.

2. In a car truck, a side frame having a top chord, a bottom chord and spaced guide columns forming a central opening in the frame, the portion of the bottom chord between said columns being in the form of an upwardly opening channel with a web which curves upwardly from the center toward the ends of the chord and upright side flanges which have horizontal top edges throughout the major portion of the space between the columns and which have upwardly projecting guide portions adjacent the columns, a semi-elliptic leaf spring having a central portion seated upon the web of the bottom chord substantially midway between the columns and end portions curved upwardly away from said web and terminating adjacent the columns between the upwardly projecting portions of said flanges, and a transom having an end portion guided for vertical movement in said opening, the end portion of the transom having portions extending into the spaces between the upwardly projecting portions of said flanges and resting upon said springs and a flat seating portion engageable with the top edges of said flanges, said transom having shoulders engageable with the inner sides of said columns and depending flanges overlapping the flanges of the bottom chord.

3. In a car truck, a side frame having a top chord, a bottom chord and spaced guide columns forming a central opening in the frame, said columns having upper vertical guide portions, lower vertical guide portions offset outwardly with respect to the upper portions and downwardly diverging portions connecting the upper and lower guide portions, the portion of the bottom chord between the lower ends of the columns being in the form of an upwardly facing channel having a web which is downwardly arched between the columns and upright side flanges, said flanges having guide portions projecting upward. 45

ly adjacent the lower ends of the columns and horizontal top edges between said projecting guide portions, a semi-elliptic leaf spring seated upon said web midway between the columns and having its opposite ends positioned between the upwardly projecting guide portions of the flanges, and a transom having shoulders engageable with the upper vertical portions of the guide columns and an end portion guided for vertical movement between the upper portions of the columns, said end portion of the transom having lateral projections extending into the spaces between the guide portions of said flanges and resting upon the ends of said spring, said end portion of the transom having a flat bottom adapted to seat upon the flanges of the bottom chord when the transom is subjected to a predetermined load.

4. In a car truck, a side frame having top and bottom chords and spaced guide columns connecting said chords, the portion of the bottom chord between said columns being in the form of an upwardly opening channel, a transom having an end portion guided for vertical movement between said columns, a bolster yieldably supported upon the transom, a semi-elliptic leaf spring having its central portion seated in said channel and its opposite end portions supporting the end portion of the transom, and interengaging seats on the transom and bottom chord to limit the compression of said elliptic spring. 30

5. In a car truck, a side frame having top and bottom chords and spaced guide columns connecting said chords, the portion of the bottom chord between said columns being in the form of an upwardly opening channel, a transom having an end portion guided for vertical movement between said columns, a bolster yieldably supported upon the transom, and a semi-elliptic leaf spring having its central portion seated in said channel and its opposite end portions supporting the end portion of the transom, the ends of said spring being deflectable into the channel of the bottom chord to permit the end portion of the transom to seat upon said bottom chord. 35 40
